UNITED STATES PATENT OFFICE.

LOUIS A. M. PHELAN, OF CHICAGO, ILLINOIS.

AUTOMATIC ELECTRIC SWITCH.

1,282,123.

Specification of Letters Patent.

Patented Oct. 22, 1918.

Application filed September 27, 1915. Serial No. 52,857.

To all whom it may concern:

Be it known that I, LOUIS A. M. PHELAN, a citizen of the United States, residing at 232 E. Erie street, in Chicago, county of Cook, and State of Illinois, have invented new and useful Improvements in Automatic Electric Switches, of which the following is a specification.

This invention relates to automatic electric switches adapted particularly for use in connection with intermittently flashing electric signs, and other electrical devices, where the need is for a device to automatically close and open a circuit or circuits at the required intervals. One of the objects of the invention is to provide a device of such nature which shall be simple and cheap in construction and effective in operation, with no small or delicate parts requiring frequent adjustment or replacement, or liable to derangement; and which shall operate with a minimum amount of care and attention, and upon a practically negligible current consumption. Such a device, briefly described, comprises a pair of tubes, preferably of glass, which are arranged parallel to each other and designed to oscillate together about a horizontal pivot. Terminal wires, which are suitably connected to the external circuits, are fused through the walls of the tubes, ending in a gap near one end in each tube; and in each tube also is a quantity of mercury, which, in the oscillations of the tubes, will run back and forth and make and break the circuits across these gaps. The pair of tubes is oscillated by a solenoid which is cut into and out of a shunt circuit through one of the tubes; and in this latter tube also is a restricted passage in the middle of the tube to retard the mercury in its flow back and forth and measure the intervals of time between oscillations—this tube being in effect an "hour-glass." The other tube has no restricted passage and operates as a simple switch to open and close the main circuit through the sign or other device; and both tubes may be filled with nitrogen or other inert gas, but are preferably exhausted, to prevent oxidation of the mercury through arcing.

A device embodying the principles of this invention is illustrated in the accompanying drawings, in which:

Figure 1 is a view of the device in front elevation.

Fig. 2 is a similar view in rear elevation.

Fig. 3 is an enlarged axial section through the upper of the two circuit-closing tubes comprising a part of the device.

Fig. 4 is a similar section through the lower tube.

Fig. 5 is a wiring diagram of the complete device.

Fig. 6 is an end view of the device showing the clip 14.

As shown in said drawings, in Figs. 1 to 5 inclusive, an upper and a lower circuit closing tube are illustrated at 8 and 10 respectively. These tubes are secured to a bar 11, of insulating material, by means of two pairs of metal clips, 14 and 15, and 16 and 17 respectively; each tube being fitted with permanent metal caps, 20, over its ends, which are snapped into the clips. The insulating bar 11 is pivoted on a horizontal pivot pin or screw 25 which is secured in a suitable panel board 26, and, by means of an integral metal strip 27, one of the clips 16, securing the lower tube, is electrically connected to this screw. The adjacent clip 14, securing the upper tube, is connected through a similar strip 30 to a wire 31, which extends through an opening 34 through the panel board, and thence to a binding post 35 on the back of the board. The other two adjacent clips, 15 and 17, are similarly connected together, as indicated at 38, and thence through a similar wire 39, extending through a second opening 40, to a corresponding binding post 45. At the upper part of the panel board 26, and to one side of its vertical center line, is arranged a solenoid 48, with a core 49 adapted to be pulled into the coil by the energizing of its winding; and such core is connected to the insulating bar 11 by a link 50 so that the movements of the solenoid core may oscillate the pair of tubes. One end of the solenoid winding is connected through a wire 51 to the pivot screw 25.

Referring now more particularly to the construction of the two circuit-closing tubes, the upper tube 8 is best illustrated in Fig. 3. It may be made of porcelain, or other heat-resisting and insulating material, which will not be acted on by the contents of the tube, but is preferably made of glass. It is closed at both ends, and through each end is fused a wire terminal, 55 and 56, which is connected to the metal cap over that end. The ends of the two terminals are separated a small distance to form a gap

near one end of the tube, as indicated at 58, and in the tube is placed a quantity of a conducting fluid 60, preferably mercury, which, in the oscillating of the tube, can run down 5 and bridge the gap 58 to close the circuit through the tube; or can run to the opposite end of the tube and open the circuit. These wires may preferably be of nickel, which has approximately the same co-efficient of expansion 10 as glass and can therefore be fused into the ends of the tubes, and which is not acted on by mercury. In order to increase the area of contact, each wire is formed into a coil at its free end, as shown, and in order 15 to protect the tube against the heat of arcing, a sleeve 62, of porcelain, mica, or the like may be interposed between the circuit gap and the wall of the tube; although ordinarily this may not be necessary, since the 20 vacuum in the tube will effectively insulate its wall against heat.

The lower tube 10 is also partly filled with mercury, 70, but is made with a restricted passage 72 in the middle to retard the flow 25 back and forth; and in one end of the tube are two terminals with a circuit gap 73 between them, formed by fusing a wire 74 through the adjacent end of the tube, and another wire 75 through the wall of the 30 tube; the latter wire leading to the metal cap 20 over the opposite end of the tube.

Although it is believed that mercury is the best conductor to use in the two tubes it might be desirable in some instances to use 35 in one or both tubes a metallic element in finely divided particles which is not too easily fused by the heat of arcing, such as carbon, which might perhaps be timed to run through the lower tube more slowly than 40 would be practicable with mercury.

When the device is assembled, the two tubes are arranged with their circuit gaps at adjacent ends, and below the solenoid 48; and the pair of tubes is so balanced that this 45 end will always be heavier, even when all of the mercury is in the other end of the device. To aid in balancing the device, there may also be provided a depending arm 80 carrying an adjustable counter-weight 81. A stop 50 82 limits the downward movement of the heavy end of the device, and its movement in the opposite direction is limited by the limit of movement of the solenoid core into the coil.

55 The operation of the device is as follows: With the device normally in the position shown, with the heavy end of the pair of tubes down, and the mercury closing the two circuit gaps, current is led from one of the line wires, 90, through the wire 39 and clip 17 into the upper end of the lower tube, thence through the tube, by means of the

mercury in it, to the clip 16, to the pivot screw 25, through the wire 51 to the solenoid, and through the latter; returning through the line wire 91. This is a shunt circuit, the current strength being determined by the resistance in the solenoid 48. At the same time the main circuit is closed through the wires 90 and 39, the clip 15, the upper tube with its mercury bridging the circuit gap, the metal parts 14 and 30 to the wire 31, and thence through a wire 85 and through the bank of lamps, or other load 100, (Fig. 5) back to the line wire 91. But as soon as the solenoid 48 is energized it draws its core in and tilts the tubes into their opposite position, when the mercury will immediately break the circuit in the upper tube and switch off the lights. The circuit through the lower tube will, however, remain closed, keeping the solenoid energized and the heavy ends of the tubes raised, with the upper circuit open and the lights off, until sufficient mercury has run down through the restricted passage to uncover the circuit gap in the lower tube; when the solenoid will be demagnetized and the tubes will drop back to their normal position as shown. The mercury will then start to run back through the restricted passage and the tubes will remain in this position until sufficient mercury has run through to reestablish the circuit through the lower tube, when the operation will be repeated as before, and thus ad infinitum.

When the device is used on a direct current, it is preferable to make the wire 90 a positive wire and the wire 91 a negative wire, as indicated. This will make the two terminals 56 and 75 in the tubes anodes, and the terminals 55 and 74 cathodes, so that the arcing will be from the mercury to the wires; and particles of mercury which are dispelled and deposited upon the wires will eventually drop off again and be again picked up by the rest of the mercury.

I claim as my invention:

A switching device comprising a frame mounted pivotally, automatic means for periodically tilting or oscillating said frame, a plurality of pairs of electric contact sockets on said frame, demountable switch tubes carried by said sockets, said tubes each having spaced terminals and current conducting fluid for opening and closing the circuits respectively, according to the tilt of said frame, one of said tubes being restricted and adapted for slow action and being connected for controlling said automatic means.

In witness whereof, I have hereunto subscribed my name this 24 day of September, 1915.

LOUIS A. M. PHELAN.
